PAPER GUIDE MEANS FOR PATTERN DUPLICATING MACHINE

Frank J. Cutri, Brooklyn, N.Y., assignor to Carlton Paper Corp., Brooklyn, N.Y., a corporation of New York

Filed June 30, 1965, Ser. No. 468,412
6 Claims. (Cl. 101—131)

This invention relates to spirit duplicating machines and is a continuation in part of my prior U.S. application Serial No. 451,478, filed April 28, 1965 for pattern duplicating machine.

More particularly, the present invention relates to a spirit duplicating machine which makes it possible to transfer a pattern from a master sheet to a copy sheet which has been moistened with spirit so as to receive an impression of the pattern carried by a master sheet, in a well known manner.

My aforesaid prior application is directed, among other features, to a rotary main roller and a counter roller cooperating therewith to press against each other a master sheet and a copy sheet which pass together between the main and counter rollers. The copy sheet is guided along a given path to the main roller, and along this latter path there is situated, spaced from the main roller, moistening means for applying spirit to that face of the copy sheet which subsequently is pressed against the master sheet. The structure further includes a pressure roller which presses the copy sheet against the main roller just prior to engagement of the copy sheet with the master sheet, and this pressure roller engages the face of the copy sheet which has just previously been moistened by the moistening means.

In a machine of this type, the master sheet and copy sheet are fed from holders through the main feed roller and counter roller, and hence to pickup rollers. The master sheet roller must be loosely supported by their holders, without the use of braking devices or other tension devices. This makes it very difficult to assure accurate registration of the two rolls, throughout their movement, and such accurate registration is essential for perfect pattern duplication. The problem is particularly serious in connection with the master pattern roll, since the master sheet is commonly rewound each time that it is being used.

One object of this invention is to provide improved guide means for guiding the master roll from its holder to its point of contact with the copy paper, so as to make it possible, by extremely simple manual manipulation, to shift the position of the master sheet while it is being fed, to insure its accurate registration with the copy paper.

It is particularly important that the guide means be simple in construction, and that the manipulation required to shift the paper be extremely easy to handle.

In accordance with a preferred embodiment of the invention, I provide, for such guide means, a holder for loosely supporting a roll of the master sheet parallel to and spaced from the main and counter rollers, together with first, second and third idler rollers and a rod all parallel to and spaced from each other and said holder and main and counter rollers. The first idler roller is located above the holder and in front of the main and counter rollers. The second idler roller is located between the first idler roller and the main and counter rollers. The third idler roller is located in front of and above the level of the first and second idler rollers. The rod is located between the second and third idler rollers and intersects the line tangent to the top of the second idler roller and the bottom of the third idler roller.

Accordingly the master sheet can be extended from the holder over the front and top of the first idler roller,

2

under, behind and over the second idler roller, under the rods, under, in front of and over the third idler roller and back under the rod, the master sheet being thereby engaged in double thickness by the rod.

5 Further in accordance with the invention, the line tangent to the bottom of the rod and the press line of the main and counter rollers is also tangent to the top of the second idler roller so as to maintain the master sheet in double thickness between the rod and the second idler roller when extended from the rod to the main and counter rollers. Optionally, adjustable braking means for the second idler roller are provided.

As a result of the above construction, the guide means is adapted to maintain the master sheet under sufficient 15 friction along a sufficiently long path so that finger pressure on the master sheet adjacent either side edge thereof against the first idler roller causes shifting of the master sheet on the idler rollers in the direction outwardly of such side edge. Put in other terms, the operator 20 can stand in front of the machine, watching the feeding of the master sheet and copy sheet. If the master sheet moves slightly out of alignment, the operator need only exert finger pressure upon the master sheet, against the first idler roller, adjacent the appropriate side edge of the 25 master sheet, so as to cause correcting shifting of the master sheet to maintain the desired registration thereof with the copy sheet.

Other objects and advantages of the invention will 30 become apparent from the following description in conjunction with the annexed drawings, which form part of the application, and in which:

FIG. 1 is a schematic side elevation of the machine of the invention;

FIG. 2 is a fragmentary elevation of the machine of 35 the invention as seen from one side;

FIG. 3 is a top plan view, partly in section, on line 3—3 of FIG. 1;

FIG. 4 is a fragmentary view similar to FIG. 3 and 40 showing the manner in which the position of the master sheet can be adjusted; and

FIG. 5 is a section on line 5—5 of FIG. 3.

Upon reference to the drawings in detail, and initially to FIG. 1, it will be seen that the structure includes a main roller 10 which is illustrated as turning in a clockwise direction, this main roller cooperating with a counter roller 12 which is situated directly over the main roller 10 for pressing together the master sheet M and copy sheet C. A moistening means 14 is provided for applying spirits to that face of the copy sheet C which subsequently is placed against the master sheet M by the rollers 10 and 12.

45 A means is provided for guiding the copy sheet C along a different path to the main roller 10, and this latter means includes the structure for positioning the copy sheet supply roll 16 as well as the turnable guide roll 50 18 around which the copy sheet passes before reaching the main roll 10. It will be noted that the moistening means 14 is spaced from the main roller 10.

Instead of simply being moistened just prior to engaging the master sheet, the copy sheet is further engaged 55 by a pressure roller 20 which cooperates with the main roller 10 to press the copy sheet against the main roller 10 just prior to engagement of the master sheet by the copy sheet. This pressure roller 20 thus serves to impress the spirit into the fibers of the copy sheet C and to 60 distribute the film of spirit uniformly over the copy sheet so that the quality of the copy is enhanced by the pressure roller 20.

65 The master sheet M moves from the master sheet supply roll 42 (FIG. 2) around first, second and third idler rollers 200, 201 and 202, and rod 203 and then along stationary guide member 26 and around the counter roller 12 to the master sheet pickup roll 28. The copy sheet C

travels from the supply roll 16 around the guide roll 18 and the master roll 10 to the copy sheet pickup roll 30.

Upon reference to FIGS. 3 and 4, it will be noted that the machine includes a frame means 34 having a pair of sidewalls 36a and 36b. The counter roller 12 includes a shaft 50 supported for rotation within slide blocks 54 (only one shown), which are guided for vertical movements in suitable openings 56 (only one shown) formed in the sidewalls 36b and 36a respectively. Springs (not shown but similar to the corresponding springs described below and used in conjunction with roller 10) urge the slide blocks 54 downwardly, and thus the counter roller 12 is supported by rotation by bearing means supported by the frame means 34 for movement toward and away from the main roller 10.

The shaft 38 which carries main roller 10 is supported for rotation by bearings (not shown) which are directly carried by the sidewalls 36a and 36b, respectively, so that the axis of rotation of the main roller 10 is fixed. Reduced shaft portions of the main roller shaft 10 respectively carry circular cam rings 42 (one shown) adjacent to and outside of the sidewalls 36a and 36b, respectively. A sprocket wheel 46 is fixed to shaft 38 and is driven by chain 48 which is in turn driven from a suitable motor (not shown), so that the main roller 10 is directly driven in order to operate the machine.

Reduced portions of the shaft 50 of the counter roller 12 turnably carry a pair of identical levers 62 (one shown) either of which can be manually turned by the operator, and these levers 62 respectively carry cams 64 which can respectively be turned into and out of engagement with the cam rings 42 in a manner described in greater detail below.

Any suitable meshing gears (not shown) may be provided on shafts 38 and 50 so that the drive is transmitted from main roller 10 to counter roller 12. This is fully explained in my aforesaid prior application. Outwardly of wall 36b, shaft 50 fixably carries a sprocket 68 which through a chain 70 drives a second sprocket 72 carried by the shaft 74 on which the master sheet takeup roll 28 is wound. Optionally, shaft 74 may be driven from sprocket 72 through any suitable slip clutch (not shown). Shaft 74 also carries a further sprocket (not shown) which through a suitable chain 80 drives the shaft 84 which carries the copy sheet pickup roll 30. These shafts 74 and 84 are supported for rotation by the sidewalls 36a and 36b of the frame means 34.

The moistening means 14 includes a trough 88 and a moistening roller 92 which dips into the spirit within trough 88 and which of course is capable of engaging the face of the copy sheet C which is to be subsequently pressed against the master roller M, as pointed out above. The trough 88 is mounted for movement about a pivot 94 so as to permit adjustments of the trough position. The roller 92 is mounted on a shaft (not shown) which carries a gear which meshes with a gear on shaft 38, so that the roller 92 is driven in unison with the main roller 10. The details of such drive are fully set forth in my aforesaid prior application. The trough 88 is supported by side extensions 90 (one shown) which are turnably mounted upon shaft 38. As a result, the trough 88 can be moved about the axis of shaft 38, while the respective gears remain in mesh.

In order to raise and lower the moistening means 14, the trough 88 has a downwardly directed surface engaged by one or more cams 98 (one shown), and these cams 98 are fixedly carried by a rotary shaft 100 supported for rotation by the sidewalls 36a and 36b of the frame means 34 and fixedly carrying a manually turnable lever 102. Thus, the operator by turning the lever 102 can turn the cams 98 so as to raise and lower the moistening means 14. Any suitable means is provided for maintaining the lever 102 in selected position. Optionally, the cams 98 are provided with flats, as exemplified by the flat 98x, which flat is horizontal and uppermost and flush against

the flat bottom of trough 88 in the cam position corresponding to the lowermost trough position.

Means are provided to adjust the height and tilt position of the raised trough 88. Horizontal block 9 is fixed to vertical side frame pieces 8b by means of screws 8. A pair of screws 7 are adjustably threaded downwardly through threaded bores of block 9, with the screw heads above the block and their tips below the block. The tips of screw 7 abut the top of an end wall of trough 88 when the trough is raised. If the tips of screws 7 are in a common horizontal plane, trough 88 will be horizontal. If slight tilting of trough 88 about the axis of roller 92 is provided, this can be obtained by appropriate adjustment of the abutment screws 7. Also, the adjusted position of these screws determines the height to which the trough can be raised. Accordingly, the screws 7 provide means to adjust the tension of copy sheet C against roller 92.

The pressure roller 20 is mounted for rotation through a structure which is almost identical with that which mounts the counter roller 12 for rotation, except that the structure for mounting the pressure roller 20 is, of course, oriented differently. The shaft 20a of pressure roller 20 is carried by bearings which are supported for rotation by slide blocks 112 (one shown), and these blocks are guided for movement in openings 114 (one shown) of the sidewalls 38a and 38b of the frame means 34. A spring 116 forms a spring means urging the slide block 112 towards the main roller 10, so that while the counter roller 12 is urged downwardly toward the main roller, the pressure roller 20 is urged upwardly into engagement with the main roller 10. In a plane which is perpendicular to the axes of the rollers 10, 12 and 20, the line which interconnects the axes of the rollers 10 and 12 meets with the line which interconnects the axes of the rollers 10 and 20 at an angle greater than 90 degrees but less than 180 degrees.

As will be apparent from my aforesaid prior application, the shaft of the pressure roller can carry a gear 40 which meshes with a gear on shaft 38 so that the drive for the main roller 10 serves to drive pressure roller 20, in addition to counter roller 12.

Also, reduced portions of the shaft of the pressure roller 20 turnably carry the manually turnable levers 120 (one shown) which respectively carry cams 122 (one shown) capable of engaging the circular cams 42 carried by the main roller shaft 38. The front edges of the plates 36a and 36b are formed with downwardly and rearwardly inclined notches 124a for receiving the shaft 124 on which the copy supply roll 16 is mounted.

A pair of brackets 126 and 128 are fixedly carried by the wall 36b to permit the swinging of the lever 120, and a similar pair of brackets 130 and 132 are provided for determining the end positions of the lever 62. Similar brackets (not shown) may be provided for the corresponding levers on the other wall 36a. These brackets can frictionally engage the levers to retain them in their end positions or any other suitable means such as a releasable detent structure or the like may be used for this purpose.

The shaft 124 which carries the copy sheet supply roll 16 fixedly carries a grooved brake pulley 134, and the wall 36b fixedly carries a pin 136 to which one end of a brake band or rope 138 is fixed, this braking element 65 138 passing around the pulley 134 and carrying a weight 140, so that through this construction the rotation of the supply roll 16 is suitably braked.

With the above-described structure, during normal operation the drive will be transmitted from the main roller by means of the above-mentioned transmissions to the counter roller 12, the pressure roller 20, and the take-up rolls through the chain and sprocket drives described above, and to the moistening roller 92, also described above.

Whenever it is desired to thread the machine the

operator need only turn the levers to displace the counter roller 12 and pressure roller 29 away from the main lever 10, so that the threading operation can be very easily carried out. At the same time, the operator can turn the lever 102 so as to lower the moistening means 14, and in this way also the threading operations need not be hampered by the moistening means.

It will be appreciated that the mechanisms associated with the rollers 10, 12 and 29 and the moistening means 14 are described and claimed in my aforesaid application, and this invention has particular reference to the guide means for the master sheet M, and particularly the idler rollers 200, 201 and 202 and guide rod 203 referred to above.

The frame means 36 includes, in addition to the wall 36a and 36b referred to above, any suitable base framework including front leg means 205. A laterally extending trough 206 is secured to leg means 205 by means of bracket 207. The master sheet supply roll 22 is loosely and turnably received upon the semi-cylindrical inner surface of trough 206, as shown in FIG. 2, with the master sheet 19 being drawn upwardly from the rear of the roll, as shown in the drawing. The roll 22 may be wound on any suitable spindle 208.

The first idler roller 200 is mounted on shaft 209, the ends of which are turnably received in extensions 210 of the respective frame walls, one such extension 210 being shown in FIG. 2. Accordingly, the first idler roller 200 is located at the front of the machine, above the roll 22, with the axis of roll 200 slightly below the level of the axis of roller 10. The paper M is carried over the front and the top of roller 200.

The roller 201 is located closer to the rollers 10 and 12 than roller 202 and rod 203, the roller 201 being supported upon shaft 211 the ends of which are journaled in the frame walls 36a and 36b. The paper is threaded under, around the rear of and over roller 201. The run M1 of the paper M between the top of roller 200 and the bottom of roller 201 is optionally substantially horizontal.

The roller 202 is supported upon shaft 212, which shaft is journaled within the frame walls 36a and 36b. Roller 202 is located intermediate the front or first idler roller 200 and rear or second idler roller 201, and is located above the level of roller 201. The paper is threaded in a run M2 from a point P1 of roller 201 near its top to a point P2 of roller 202 near its bottom and is threaded around the front and over the top of roller 202. The ensuing rearward return run of the paper is designated by the reference character M3.

The rod 203 is provided with extensions of reduced diameter which extend through the frame walls 36a and 36b, outwardly of which they are threaded to receive tightening nuts 213, so as to prevent turning of rod 203. The two runs M2 and M3 extend under rod 203, and the vertical position of rod 203 is such that it bears frictionally against the two runs M2 and M3, as shown in FIG. 1. The paper rearwardly from rod 203 passes over the top of support 25 and hence between the rollers 10 and 12. The top surface of support 25 is downwardly inclined slightly so as to correspond with the inclination of the paper passing over it, to insure smooth support of the paper. The position of rod 203 relative to roller 201 is such that the run of paper M4 between rod 203 and the rollers 10 and 12 remains in substantial flush contact with the run M2 until the point P1 of roller 201 is reached.

From the foregoing, it will be apparent that the folder 206 serves loosely to support the roll 22 parallel to and spaced from the respective main and counter rolls 10 and 12. The first, second and third idler rollers 200, 201 and 202 and the rod 203 are all parallel to and spaced from each other and from the holder and from the main and counter rollers. The first idler roller 200 is above the holder 206 and in front of the main counter rollers 10

and 12. The second idler roller 201 is between the first idler roller 200 and the main and counter rollers 10 and 12. The third idler roller 202 is in front of the second idler roller 201 and above the level of the first and second idler rollers 200 and 201. The rod is between the second and third idler rollers 201 and 202 and intersects the imaginary line which can be drawn between the points P1 and P2, this being substantially the line which would be tangent to the top of the second idler roller 201 and the bottom of the third idler roller 202. Accordingly, the master sheet M extended from the holder over the front and top of the first idler roller 200, under, behind and over the second idler roller 201, under rod 203, in front of and over the third idler roller 202 and back under rod 203 is frictionally engaged in the double thickness of runs M2 and M3 by such rod 203.

It is further clear that the imaginary line which is tangent to the bottom of rod 203 and the contact or press line of the main and counter rollers 10 and 12 is tangent to the top of the second idler roller, substantially engaging it at points P1, so as to maintain the master sheet M in engaging double thickness in the portions of the runs M2 and M3 between rod 203 and the point P1 when the paper is extended from the rod to the main and counter rollers in the manner shown. Since it is difficult to show the two thicknesses of paper, for convenience the drawing shows the arrow 214 designating the path of movement of the run M2 between the point P1 and the rod 203 while the arrow 215 is provided to designate the direction of movement of the run M3 between the rod 203 and the point P1. The run M4 serves as a coplanar extension of the portion of run M3 between rods 203 and point P1.

In order further to provide the desired tension upon the paper M, a brake is provided for the shaft 211 carrying the second idler roller 201. This brake is shown generally in FIG. 3 and is shown in detail in FIG. 5. The brake comprises a continuous, somewhat bendable metal strap 220 which is extended around the stationary rod 203 and the shaft 211. Thus, the strap 220 has two generally parallel legs 220a, connected by a loop 220b around the side of rod 203 remote from shaft 211, and connected at the other end by a convex loop 220c which extends conformingly around shaft 211. The inside of loop 220c is faced by a brake lining or friction material 222, optionally leather. A pin 221 extends transversely through rod 203 in a direction perpendicular to the arms 220a, and extends loosely through openings 223 in such arms 220a, so as to prevent the brake device from shifting in the direction of the axis of rod 203.

The tension of the brake material 222 upon shaft 211 is controlled by bolt 224 and nut 225. The bolt 224 extends perpendicularly through the arms 220a, intermediate rod 203 and shaft 211, said bolt 224 having a head 226 adjacent one arm 220a. The nut 225 is screwed onto the threaded bolt 224 against the other arm 220a and it will be apparent that the tightening or loosening of nut 225 causes corresponding adjustment in the braking tension upon shaft 211.

The guide means, as the result of the foregoing construction, is adapted to maintain the master sheet M under sufficient friction over a sufficiently long path so that finger pressure on the master sheet adjacent either side edge thereof against the first idler roller 200 causes shifting of the master sheet M on the idler rollers in the direction outwardly of such side edge. Thus, the fragmentary view of FIG. 4 shows the master sheet M and shows one of the side edges 230 thereof. The view also illustratively shows pressure exerted by the operator's finger 231 upon the sheet M against the first idler roller 200, adjacent such side edge 230. The result of such pressure is to cause a gradual outward shifting of sheet M, in the direction of arrow 232, to the position M' of the master sheet M illustratively shown in broken lines in FIG. 4.

It will be apparent that the desired tension upon the master sheet M, permitting the desired operating adjustment result, is obtained as a result of the selected friction upon the roller 201 from the brake referred to above, coupled with the tension resulting from the location and stationary condition of rod 203, and the manner in which the two runs M2 and M3 are in flush abutment between rod 203 and point P1, all as discussed above in detail. The result of the added tension exerted by the finger 231 is to enable the opposite side of the sheet M to travel slightly faster, and this causes a corresponding compensating movement of the sheet in the direction of arrow 232.

The rolls 74 and 84 are provided with a plurality of pairs of corresponding markings corresponding to various widths of pattern paper which are used in conjunction with the machine. For example, FIG. 3 illustratively shows a pair of markings 235 on each roller 74 and 84 corresponding to the narrowest width of paper which is to be used, and shows other marking pairs 235a corresponding to an intermediate width of paper. However, these markings are used only for the initial threading of the paper from the roll 221, on the path above described, to the passage between the two rollers 10 and 12. This insures initial proper lateral registration of the master sheet M with the copy sheet C. The rolls 200, 201 and 202 and rod 203 are provided with other pairs of markings, such as the illustrated pairs 236 and 236a, corresponding to different widths of paper. In this particular instance, which is an illustrative example, the width of paper corresponds to the markings 235a on the one hand and 236a on the other hand. Accordingly, initial threading of the paper is in line with the markings 235a. This means that while the paper is running, it should be aligned with the markings 236a. Illustratively, the paper M shifted slightly laterally to the left. The pressure exerted by finger 231 was sufficient to return the paper to the broken line position M', in which the edge 230 is again aligned with the markings 236a. Accordingly, it is extremely simple for the operator of the machine to watch the paper, while it is being fed through the machine, and to exert finger pressure upon master sheet M, at any necessary time, so as to maintain the paper M guided upon the correct pair of markings upon the idler rollers and the rod 203.

While I have disclosed a preferred embodiment of my invention, and have indicated various possible changes, omissions and additions which can be made in the invention, it will be apparent that various other changes, omissions and additions may be made in the invention without departing from the scope and spirit thereof.

What is claimed is:

1. Paper guide means for a machine of the type described having a main feed roller, a counter roller parallel to and coacting with said main roller for pressing against each other a master sheet and a copy sheet which pass together between said main and counter rollers, said guide means comprising a holder for loosely supporting a roll of said master sheet parallel to and spaced from said main and counter rollers, and first, second and third idler rollers and a rod all parallel to and spaced from each other and said holder and main and counter rollers, said first idler roller in front of said main and counter rollers, said second idler roller between said first idler roller and said main and counter rollers, said third idler roller in front of the second idler roller and above the level of said first and second idler rollers, said rod between said second and third idler rollers and intersecting the line tangent to the top of said second idler roller and the bottom of said third idler roller whereby the master sheet extended from said holder over the front and top of said first idler roller, under, behind and over the second idler roller, under the rod, under, in front of and over the third idler roller and back under the rod and then between said main and counter rollers is frictionally engaged in double thickness by said rod, said guide means being thereby

adapted to maintain said master sheet under sufficient friction along a sufficiently long path so that finger pressure on said master sheet adjacent either side edge thereof against said first idler roller causes shifting of said master sheet on said idler rollers in the direction outwardly of said side edge.

2. Guide means according to claim 1, the line tangent to the bottom of said rod and the press line of said main and counter rollers being tangent to the top of said second idler roller so as to maintain the master sheet in double thickness between said rod and said second idler roller.

3. Guide means according to claim 1, said guide means also comprising adjustable means braking said second idler roller.

4. Guide means according to claim 2, said guide means also comprising adjustable means braking said second idler roller.

5. In a spirit duplicating machine, a main feed roller, a counter roller parallel to and coacting with said main roller for pressing against each other a master sheet and a copy sheet which pass together between said main and counter rollers, means directing a copy sheet along a given path to said main roller, moistening means situated along said path in advance and spaced from said main roller for moistening the copy sheet with spirit at that face of the copy sheet which is subsequently pressed against the master sheet by coaction of said main and counter rollers, and means for guiding said master sheet to said main and counter rollers so as to permit manual adjustment of the master sheet to maintain registration thereof with the copy sheet, said guide means comprising a holder for loosely supporting a roll of said master sheet parallel to and spaced from said main and counter rollers, and first, second and third idler rollers and a rod all parallel to and spaced from each other and said holder and main and counter rollers, said first idler roller above said holder and in front of said main and counter rollers, said second idler roller between said first idler roller and said main and counter rollers, said third idler roller in front of the second idler roller and above the level of said first and second idler rollers, said rod between said second and third idler rollers and intersecting the line tangent to the top and said second idler roller and the bottom of said third idler roller whereby the master sheet extended from said holder over the front and top of said first idler roller, under, behind and over the second idler roller, under the rod, under, in front of and over the third idler roller and back under the rod is frictionally engaged in double thickness by said rod, the line tangent to the bottom of said rod and the press line of said main and counter rollers being tangent to the top of said second idler roller so as to maintain the master sheet in double thickness between said rod and said second idler roller when extended from said rod to said main and counter rollers, said guide means being adapted to maintain said master sheet under sufficient friction along a sufficiently long path so that finger pressure on said master sheet adjacent either side edge thereof against said first idler roller causes shifting of said master sheet on said idler rollers in the direction outwardly of said side edge.

6. Apparatus as claimed in claim 5, said apparatus also comprising a brake mounted upon said rod and bearing frictionally against said second idler roller, and means for adjusting the tension of said brake against said second idler roller.
